RAY S. WILBUR, OF LYNDHURST, AND RAY F. LOVELEE, OF EAST ORANGE, NEW JERSEY, ASSIGNORS TO WESTERN ELECTRIC COMPANY, INCORPORATED, OF NEW YORK, N. Y., A CORPORATION OF NEW YORK.

TELEPHONE TRANSMISSION SYSTEM.

1,364,013.

Specification of Letters Patent. Patented Dec. 28, 1920.

Application filed December 11, 1917. Serial No. 206,642.

To all whom it may concern:

Be it known that we, RAY S. WILBUR and RAY F. LOVELEE, citizens of the United States, residing at Lyndhurst, in the county 5 of Bergen, State of New Jersey, and at East Orange, in the county of Essex, State of New Jersey, respectively, have invented certain new and useful Improvements in Telephone Transmission Systems, of which the 10 following is a full, clear, concise, and exact description.

This invention relates to telephone repeater circuits, and more particularly to two-way, two-repeater circuits with which 15 is associated means for amplifying ringing current or other signaling current, as well as telephonic currents.

An object of this invention is to provide a system of this character in which the 20 length of line over which signaling devices may be satisfactorily operated is increased.

In accordance with the features of this invention, a telephone repeater circuit having an incoming and an outgoing line section 25 connected at a repeater station through a repeater of the well known vacuum tube type for amplifying both telephonic and ringing currents, and in which the input side of the repeater is connected with the 30 incoming line section through a potentiometer and possibly a frequency filter for obtaining the greatest possible gain in amplification of the telephonic currents, is provided with means, preferably in the form 35 of an electromagnetic switching device, responsive to amplified ringing current from the incoming line section to connect the input side of the repeater to that line section independently of the potentiometer and 40 filter.

This invention will be best understood from the following description when considered in connection with the accompanying drawing in which is shown a two-way, 45 two-repeater telephone circuit containing one embodiment of this invention.

Referring to the drawing, there are shown two sections 11 and 12 of a telephone line, which are joined through repeater apparatus at a two-way, two-repeater station. 50 The repeater arrangement comprises two vacuum tube repeaters 13 and 14 and their associated apparatus, repeater 13 being adapted to receive signals transmitted to

the station over line section 11 and to transmit amplified copies of these signals from the station over the line section 12. In a similar manner repeater 14 amplifies signals received over line section 12 and transmits such amplified signals over line section 11. 55 The input circuit for repeater 13 comprises impedance coils 15, 15 and condensers 16, 16 which coöperate and serve as a frequency filter for filtering out frequencies above the talking range, a potentiometer 17, normal 60 contacts of relay 18, and the primary winding of repeating coil 19. The secondary winding of this repeating coil 19 is in circuit with battery and the filament and the grid of the repeater 13. The filament and 65 the plate of the repeater 13 are connected in circuit with the primary winding of an output repeating coil 20, the secondary windings of which are connected in the line section 12. A relay 21, having two electro- 70 magnets in series with a condenser 22 connected in bridge of another condenser 23, is in series with the primary winding of the output repeating coil 20. Condenser 23 is of such capacity that when connected in circuit with the primary winding of the output coil 20 the circuit is resonant to currents of talking frequencies and the condenser 22 75 is of such capacity that when connected in circuit with the windings of the relay 21 80 this circuit is resonant to currents of ringing frequency. It will be understood therefore that relay 21 will not be affected by telephonic currents. An artificial balancing line 24 is connected in circuit with the secondary winding of the output repeating coil 20. The input circuit of repeater 14 comprises impedance coils 25, 25 and condensers 26, 26, which coöperate and serve as a filter 85 to filter out frequencies above the talking 90 range, a potentiometer 27, normal contacts of relay 28 and the primary winding of an input repeating coil 29, the secondary of 95 which is connected in circuit with battery and the filament and the grid of a repeater 100 14. The filament and the plate of the repeater 14 are in circuit with the primary winding of the output repeating coil 30, the secondary windings of which are connected in the line section 11. Relay 31 and condensers 32 and 33 are associated with the 105 output repeating coil 30 in precisely the same manner as relay 21 and the condensers

22 and 23 are associated with the output repeating coil 20, and function in the same manner. An artificial balancing line 34 is also associated with the output repeating 5 coil 30.

It will be assumed that ringing current or other current having characteristics different from those of telephonic currents is transmitted to the repeater station over the 10 line section 11. This ringing current passes from the line section 11 through the secondary windings of the output repeating coil 30, the impedance coils 15, 15, potentiometer 17, normal contacts of the relay 18 and the 15 primary winding of the input repeating coil 19. Current is thereupon induced in the secondary circuit which includes the filament and grid of the repeater 13 and is thereby amplified and repeated into the circuit including the winding of relay 21. Relay 21 is 20 thereupon operated to open its contact, releasing relay 40. Relay 18 is thereby operated over a circuit from battery through the windings of relay 18 and the contact of relay 40 to ground. Relay 18 in operating closes its alternate contacts, the upper and middle of which connect the primary winding of the repeating coil 19 direct to the line section 11, and the lower of which establishes 25 a short circuit for the primary winding of the output repeating coil 30. The operation of relay 18 also opens its normal contacts, removing the potentiometer and the frequency filter from circuit relation with the 30 primary winding of the input repeating coil 19. When ringing current incoming from the line section 11 first traverses the secondary windings of the output repeating coil 30, there may be sufficient current induced in the primary thereof to operate relay 31, thereby momentarily releasing relay 41 and operating relay 28. However, if 35 this condition exists, it is for but a very short period, for, as soon as the amplified ringing current operates relay 21, relay 40 releases to permit the operation of relay 18. Relay 18 then short-circuits the primary winding of the output repeating coil 30 in the manner already described. Relay 31 40 will therefore immediately release, permitting relay 41 to operate and open the circuit of relay 28. In other words, while both relays 21 and 31 may be operated by ringing current incoming to the repeater station 45 from either line section, only the relay receiving amplified ringing current will remain operated. Amplified ringing current traversing the windings of relay 21 also traverses the primary winding of the output repeating coil 20, and as a result amplified ringing current is induced into the secondary windings thereof, which are in circuit with the line section 12. This ringing current transmitted over line section 11, 50 amplified at the repeating station as de-

scribed, and then induced into the line section 12, may be employed to operate signaling devices of any suitable character.

From this brief description it is thought it will be clearly understood that the apparatus 70 functions to receive ringing current incoming over line section 12, to amplify and then to transmit such amplified current into line section 11.

What is claimed is:

1. A telephone transmission system comprising two line sections, a repeater for amplifying talking and ringing currents, a potentiometer normally connecting the input side of the repeater with one line section, an output repeating coil connecting the output side of the repeater with the other line section, and means connected in circuit with the output side of the repeater and responsive to ringing current to cause the disconnection of the potentiometer from the circuit while ringing. 75

2. A telephone transmission system comprising two line sections, a repeater for amplifying talking and ringing currents, a potentiometer normally connecting the input side of the repeater with one line section, an output repeating coil connecting the output side of the repeater with the other line section, a relay connected in circuit with the output side of the repeater and the primary winding of the output repeating coil, and responsive to ringing current over the one line section to cause the connection of the repeater thereto independently of the 95 potentiometer. 100

3. A telephone transmission system comprising two line sections, a repeater for amplifying talking and ringing currents, a potentiometer normally connecting the input side of the repeater with one line section, means connecting the output side of the repeater with the other line section, and a relay in circuit with the output side of the repeater and responsive to ringing current incoming from the one line section for 105 causing the connection of the input side of the repeater thereto independently of the potentiometer while ringing. 110

4. A telephone transmission system comprising two line sections, a repeater for amplifying talking and ringing currents, a potentiometer normally connecting the input side of the repeater with one line section, means connecting the output side of the repeater with the other line section, a relay in circuit with the output side of the repeater and responsive to ringing current incoming from the one line section, and a second relay operating upon the response of 120 the first relay to connect the input side of the repeater to the one line section independently of the potentiometer. 125

5. A telephone transmission system comprising two line sections, a repeater for 130

amplifying talking and ringing currents, a frequency filter and a potentiometer normally connecting the input side of the repeater with one line section, an output repeating coil connecting the output side of the repeater with the other line section, a relay connected in circuit with the output side of the repeater and the primary winding of the output repeating coil and responsive to ringing current incoming from the one line section, and a second relay energized upon the response of the first relay to disconnect the potentiometer and the frequency filter from the repeater and to connect the repeater to the one line section independently of the potentiometer and frequency filter.

6. A telephone transmission system comprising two line sections, a repeater for amplifying talking and ringing currents, a potentiometer normally connecting the input side of the repeater with one line section, an output repeating coil connecting the output side of the repeater with the other line section, and means responsive to amplified ringing current to connect the input side of the repeater with the one line section independently of the potentiometer.

7. A telephone transmission system comprising two line sections, a repeater for amplifying talking and signaling currents having its output side connected with one line section, means controlling the amplifi-

cation of the repeater normally connecting the input side thereof with the other line section, and means responsive to amplified signaling current to connect the input side of the repeater with said other line section independently of the amplification controlling means.

8. A telephone transmission system comprising two line sections, a repeater for amplifying talking and signaling currents having its output side connected with one line section, current regulating means normally connecting the input side of the repeater with the other line section, and means responsive to amplified signaling current to connect the input side of the repeater with said other line section independently of the current regulating means.

9. In a transmission system comprising two line sections, a repeater for amplifying talking and signaling currents having its input circuit connected with one section and its output circuit connected with the other section, and means responsive to amplified signaling current for increasing the efficiency of the system to signaling current.

In witness whereof, we hereunto subscribe our names this 6th day of December, A. D. 1917.

RAY S. WILBUR.
